CLAIM

We claim the ornamental design for a bowl, as shown and described.

DESCRIPTION

FIG. 1 is a bottom isometric view of a bowl;

FIG. 2 is a top plan view of the bowl of FIG. 1;

FIG. 3 is a bottom view of the bowl of FIG. 1;

FIG. 4 is a front elevation view of the bowl of FIG. 1;

FIG. 5 is a rear elevation view of the bowl of FIG. 1;

FIG. 6 is a left side elevation view of the bowl of FIG. 1; and,

FIG. 7 is a right side elevation view of the bowl of FIG. 1. The even length broken lines in the figures represent portions of the article that form no part of the claimed design. The uneven length broken lines in the figures illustrate boundaries and form no part of the claimed design.

1 Claim, 7 Drawing Sheets
